(57) CLAIM

The ornamental design for a compressor piston, as shown and described.

DESCRIPTION

FIG. 1 is a front elevational view of a compressor piston;
FIG. 2 is a rear elevational view thereof;

FIG. 3 is a top plan view thereof;
FIG. 4 is a bottom plan view thereof;
FIG. 5 is a right side elevational view thereof;
FIG. 6 is a right side elevational view thereof; and
FIG. 7 is a perspective view thereof.
FIG. 8 is a front elevational view of a compressor piston showing a second embodiment of my new design;
FIG. 9 is a rear elevational view of FIG. 8;
FIG. 10 is a top plan view of FIG. 8;
FIG. 11 is a bottom plan view of FIG. 8;
FIG. 12 is a right side elevational view of FIG. 8, the left side being a mirror image;
FIG. 13 is a perspective view of FIG. 8;
FIG. 14 is a perspective view of a compressor piston showing a third embodiment of my new design;
FIG. 15 is a rear elevational view of FIG. 14;
FIG. 16 is a top plan view of FIG. 14;
FIG. 17 is a bottom plan view of FIG. 14;
FIG. 18 is a right side elevational view of FIG. 14;
FIG. 19 is a left side elevational view of FIG. 14;
FIG. 20 is a perspective view of FIG. 14;
FIG. 21 is a front elevational view of a compressor piston showing a fourth embodiment of my new design;
FIG. 22 is a rear elevational view of FIG. 21;
FIG. 23 is a top plan view of FIG. 21;
FIG. 24 is a bottom plan view of FIG. 21;
FIG. 25 is a right side elevational view of FIG. 21;
FIG. 26 is a left side elevational view of FIG. 21;
FIG. 27 is a perspective view of FIG. 21;
FIG. 28 is a front elevational view of a compressor piston showing a fifth embodiment of my new design;
FIG. 29 is a rear elevational view of FIG. 28;
FIG. 30 is a top plan view of FIG. 28;
FIG. 31 is a bottom plan view of FIG. 28;
FIG. 32 is a right side elevational view of FIG. 28;
FIG. 33 is a left side elevational view of FIG. 28;
FIG. 34 is a perspective view of FIG. 28;
FIG. 35 is a front elevational view of a compressor piston showing a sixth embodiment of my new design;
FIG. 36 is a rear elevational view of FIG. 35;
FIG. 37 is a top plan view of FIG. 35;
FIG. 38 is a bottom plan view of FIG. 35;
FIG. 39 is a right side elevational view of FIG. 35, the left side elevational view being a mirror image;
FIG. 40 is a perspective view of FIG. 35; and,
FIG. 41 is a side elevational view of the compressor piston shown in FIGS. 1 through 7, the broken line showing of a compressor forms no part of the claimed design.
